UNITED STATES PATENT OFFICE.

EDWARD A. BACHMAN, OF NEW YORK, N. Y., ASSIGNOR TO LAURENCE J. SMITH, OF LOWELL, MASSACHUSETTS.

DESIGN FOR A BADGE.

SPECIFICATION forming part of Design No. 27,234, dated June 22, 1897.

Application filed April 19, 1897. Serial No. 632,868. Term of patent 7 years.

To all whom it may concern:

Be it known that I, EDWARD A. BACHMAN, a citizen of the United States, residing at New York, in the county of New York and State of New York, have invented and produced a certain new and original Design for Badges, of which the following is a full, clear, and exact description.

The design herein set forth constitutes the badge of the Benevolent Order of Foresters of America, the said design being illustrated in the accompanying drawing, which forms part of this specification.

The drawing shows the obverse, the reverse being blank.

As shown in the drawing, the leading or material feature of the design is the pendent medallion having a central representation of an antlered deer's head surrounded by a circular border representing a buckled belt, over which is placed, on the left of the belt, an oval tablet containing the representation of a female figure supporting in the right hand a rod upon which is a liberty cap, with the left hand resting upon the American shield, the whole typical of Liberty. In the upper portion or the medallion is another oval tablet, also on the belt, containing the representation of the fasces and typifying Unity.

At the right-hand portion of the medallion and upon the belt is a third oval tablet containing the representation of two male figures, one assisting the other, and typifying Benevolence, and at the bottom portion of the me-

dallion is a fourth oval tablet containing the representation of clasped human hands and typifying Concord. Between the first and second, the second and third, and the third and fourth tablets are representations upon the belt of three links, a common designation of Fraternity. The rim of the medallion is beaded. All of the figures, together with the beading, are in low relief. As already stated, the medallion, as just described, is the leading or material feature of my design.

Other but optional features of my design will be described now. The medallion is suspended by links from a bar which may contain the initials "F. of A." of the order of Foresters of America, and this bar supports the representation of a spread-eagle. A pin-bar is connected with the first-named bar by a band of ribbon containing the national colors, red, white, and blue. The top bar is designed to receive the name of the State or other jurisdiction of the individual owner of the badge.

The medallion and the bars are of metal, pressed, stamped, or otherwise produced.

What I claim is—

The design for a badge, substantially as shown and described.

In testimony whereof I have hereunto set my hand this 12th day of April, A. D. 1897.

E. A. BACHMAN.
